UNITED STATES PATENT OFFICE

2,489,773

NURSING BOTTLE JACKET

Dianne R. Hall, Los Angeles, Calif.

Application February 2, 1949, Serial No. 74,076

3 Claims. (Cl. 248—105)

1

This invention relates to novel and useful improvements in bottle holders.

An object of this invention is to support a bottle within a jacket in such a manner that the bottle is insulated from the jacket through a substantial amount through the medium of an air space which, of necessity, is provided when the bottle is inserted in the jacket.

Another object of this invention is to support a bottle by means of a structure which cushions shock when the bottle is inadvertently dropped by two independent means, the first means being longitudinal and transverse ribs disposed on the inner surface of the jacket which contact the said bottle, and additional ribs on the outside surface of the jacket. The same ribs also add to the rigidity and strength of the holder without making the holder substantially greater in thickness thereby reducing weight. The inner longitudinal ribs are so placed as to permit the corners of the nursing bottle to be inserted in between the ribs to permit easy insertion. The inner transverse ribs are used for the purpose of gripping the lower end of the nursing bottle to prevent slippage.

Another object of this invention is to support the bottle jacket in such a manner that the forward end is lower than the rear end through the medium of a pair of supports, one of which is longer than the other, and to indicate the quantity of contents of the bottle by means of eight holes which are provided on the side of the jacket opposite from the said supports.

Another object of this invention is to provide an improved structure of the general class described which is practical and commercially feasible.

Ancillary objects and features of novelty will become apparent to those skilled in the art, in following the description of a preferred form of the invention, illustrated in the accompanying drawings, wherein:

Figure 1 is an elevational side view of the preferred form of the invention, showing a bottle disposed therein;

Figure 2 is a bottom view of the device shown in Figure 1;

Figure 3 is an elevational end view of the device shown in Figure 1;

Figure 4 is an end view of the preferred form of the invention;

Figure 5 is a longitudinal sectional view taken substantially on the line 5—5 of Figure 3 and in the direction of the arrows;

Figure 6 is a transverse sectional view taken on the line 6—6 of Figure 1 and in the direction of the arrows; and

2

Figure 7 is a longitudinal view taken substantially on the line 7—7 of Figure 2 and in the direction of the arrows.

It is one of the prime purposes of the present invention to provide an attractive, commercially feasible device having various features of importance and practicability.

The invention relates generally to that class of bottle holders adaptable for use particularly in baby's feeding bottles whereby the bottle is maintained in its tilted position so that the contents thereof flow by gravity to the nipple of the bottle. When the device is used in this capacity, vision openings or holes of necessity appear at the top of the device in order that the quantity of the substance in the bottle may be readily ascertained.

Often the bottle and jacket are inadvertently dropped to the floor or to the ground. Hence, in order to substantially obviate or at least materially lessen breaking under these conditions, the device is made of resilient material, preferably of rubber or a rubber product. A number of longitudinal and transverse ribs are fixed to the interior surface of the jacket in order that the outer surface of the bottle when disposed in the jacket is spaced from the main inner surface of the said jacket. This provides an air space between the bottle and the actual jacket thereby serving in the capacity of an air insulator. Hence, if cold or warm contents are in the bottle, they will tend to remain in such thermal condition due to the presence of the air space.

The said ribs serve another function which is equally as important and that is to act in the nature of shock absorbers. The ribs themselves are resilient in nature and will flex slightly when the device is jarred. The said ribs serve a still further function of acting to lock the bottle in the jacket on a slight relative rotation therebetween.

Outer ribs are provided on the jacket for ornamental purposes and also to act as shock absorbers when and if the jacket having a bottle therein is inadvertently dropped.

The jacket generally indicated at 10 is substantially cylindrical in shape to conform generally to the general shape of the majority of commercial baby feeding bottles. Of course, if it is desired to use a rectangular device this may be done. However, it is within the contemplation of the invention to use a resilient and flexible material such as rubber.

The jacket 10 has an open end 12 for insertion of a bottle and a closure 14 at the opposite end.

This closure has a central opening 16 therein in

order to break the vacuum which is produced when pulling the bottle from the jacket and also to allow the air which would normally be compressed to be discharged when inserting the bottle in the jacket.

A bead 18 is supplied about the closure 14 and a similar bead 20 is supplied about the open end 12. These beads also serve as shock absorbing members.

A number of longitudinal ribs 22 are fixed to the interior surface of the jacket 10 and are adapted to be in actual contact with the bottle when inserted through the open end 12. These ribs serve the function of spacers for the outer surface of the bottle and the inner surface of the jacket 10. The ribs also act as shock absorbers as described previously.

A plurality of transverse ribs 24 which are substantially circular in shape are provided adjacent the bottom or closure 14 and are substantially parallel to each other. These ribs serve in the same capacity as the ribs 22.

A plurality of external longitudinal ribs 28 are provided on the outer surface of the jacket 10 serving as shock absorbers and also being used for ornamentation. One of the ribs 28 spreads at spaced intervals into circular openings or rings 30. Apertures 32 are provided in the jacket and within the confines of these rings. These apertures are for sight readings to determine the quantity of substance in the bottle. It is appreciated that in lieu of the series of openings 32 there may be provided a single elongated slot, star-shaped openings or other types of openings.

A pair of supports 34 and 36, respectively, are fixed to opposite ends of the jacket 10. The said support 34 is shorter than the support 36 and is disposed at the forward or open end of the jacket 10. Hence, if the device is placed on the supports it will be inclined toward the open end for gravity flow of fluid within the bottle toward the nipple of the bottle. Each support is composed of a pair of legs diverging toward their ends as seen best in Figure 4. The legs are formed of the same material as the jacket and the construction is preferably integral. Stiffening ribs 38 may be provided between the supports 34 and 36 and the under surface of the jacket. These stiffening ribs are of the same material as the jacket.

By inspection of Figure 1 it will be seen that the beads 18 and 20 respectively flow smoothly into the supports 34 and 36 thereby forming a pleasing contour and shape.

It is apparent that variations may be made without departing from the spirit of the invention.

Having described the invention, what is claimed as new is:

1. As a new article of manufacture, a resilient substantially cylindrical jacket for holding and insulating a bottle and having an open end for receiving a bottle, resilient longitudinal ribs on the inner surface of said jacket providing an air space between the outer surface of a bottle and the inner surface of said jacket and acting to lock the bottle in the jacket upon slight relative rotation therebetween, transverse resilient ribs fixed to the inner surface of said jacket, resilient protuberances on the outer surface of said jacket to cushion shock, a short support fixed at the front end of said jacket, and a relatively long support fixed at the rear end of said jacket.
2. As a new article of manufacture, a resilient substantially cylindrical jacket for holding and insulating a bottle and having an open end for receiving a bottle, resilient longitudinal ribs on the inner surface of said jacket providing an air space between the outer surface of a bottle and the inner surface of said jacket and acting to lock the bottle in the jacket upon slight relative rotation therebetween, transverse resilient ribs fixed to the inner surface of said jacket, resilient protuberances on the outer surface of said jacket to cushion shock, a short support fixed at the front end of said jacket, and a relatively long support fixed at the rear end of said jacket.
3. As a new article of manufacture, a resilient substantially cylindrical jacket for holding and insulating a bottle and having an open end for receiving a bottle, resilient longitudinal ribs on the inner surface of said jacket providing an air space between the outer surface of a bottle and the inner surface of said jacket and acting to lock the bottle in the jacket upon slight relative rotation therebetween, transverse resilient ribs fixed to the inner surface of said jacket, resilient protuberances on the outer surface of said jacket to cushion shock, a short support fixed at the front end of said jacket, and a relatively long support fixed at the rear end of said jacket.
